CLAIM

The ornamental design for a media tank connecting clips as shown.

DESCRIPTION

FIG. 1 is a front view thereof of my new design for a media tank connecting clips;

FIG. 2 is a left side view thereof;

FIG. 3 is a right side view thereof;

FIG. 4 is a rear view thereof;

FIG. 5 is a front right perspective view thereof;

FIG. 6 is a top right perspective view thereof;

FIG. 7 is a bottom view thereof; and,

FIG. 8 is a top view thereof.

The broken lines shown represent portions of a media tank connecting clips and form no part of the claimed design.

1 Claim, 8 Drawing Sheets
